HENRY B. BRIGGS, OF CLARKSBURG, MASSACHUSETTS.

Letters Patent No. 70,402, dated November 5, 1867.

IMPROVEMENT IN SPINNING-JACKS.

The Schedule referred to in these Letters Patent and making part of the same.

TO ALL WHOM IT MAY CONCERN:

Be it known that I, HENRY B. BRIGGS, of Clarksburg, in the county of Berkshire, and in the State of Massachusetts, have invented a new and useful Improvement in Spinning-Jacks; and I hereby declare that the following is a full, clear, and exact description thereof, which will enable those skilled in the art to make and use the same, reference being had to the accompanying drawing, forming part of this specification, in which drawing—

Figure 1, sheet 1, is a side view partly in section of so much of a jack as it is necessary to show in order to illustrate and explain my invention.

Figure 2 is a plan thereof.

Figure 3 is a rear elevation.

Figure 4, sheet 2, is a side view partly in section, which shows a modification.

Figure 5 is a plan thereof, and

Figure 6 is a rear elevation.

Similar letters of reference indicate corresponding parts.

This invention relates to spinning-jacks, and consists in devices for causing the carriage to be drawn in by the aid of the "race-belt;" the belt-guide being moved far enough toward the fast pulley to bring the belt partially upon it, and cause the race-shaft to receive more or less rotary motion, in order to aid the spinner in winding the yarn that has been spun or twisted, thereby relieving him of much of the labor of running the carriage in.

By a modification of my invention, hereinafter set forth, I accomplish the same thing by moving the fast pulley itself toward the belt, letting the belt-guide remain stationary meanwhile. I bring the belt into partial engagement only with the fast pulley because I do not desire to drive the race-shaft at this time at full speed. By bringing the belt partially on the edge of said pulley, the belt is allowed to slip somewhat on its edge, and consequently produces only a moderate speed of the shaft, (not here shown,) whose rotation accomplishes the winding of the yarn on the bobbins, and the consequent drawing in of the carriage as the winding proceeds.

Observing the figs. 1, 2, and 3, the letter A designates the head of a spinning-jack, and B the driving-shaft; D is the ordinary shipper arranged in guides over the shaft on the back part of the head. E is the belt-guide, permanently fixed to the shipper, and moving with it so as to take the belt from the fast pulley C to the loose pulley C', and *vice versa*. The shipper is moved the proper distance, at the proper times, toward the right by a lever, G, which is hung in a vertical position upon a fulcrum-pin, H, secured to a convenient part of the head, on which pin it is vibrated, as hereinafter set forth. On the upper part of the lever G is a cam, F, whose bevelled side is toward a shoulder, g, formed on the under side of the shipper, as seen in fig. 3. The lower end of lever G is connected to a rod, I, which extends along the carriage-track to its front end, or as far in that direction as is necessary; the forward end of said rod being connected to the vertical arm of a bent lever, M, which is pivoted to a standard, N, whose foot has a longitudinal slot, seen in fig. 2, to allow the standard to be adjusted to different positions on the floor for spinning hard or soft twist. A cord or belt may be substituted for the rod I, if preferred. The upper part of lever M extends backward in a general horizontal direction, and is composed of two inclined planes of about equal lengths, joined at their vertices, so that the higher portion of said horizontal part of the lever is at or near the middle of its length. The lever M is operated by the carriage L, whose axle passes over the horizontal portion of said lever and depresses it, the double inclinations of the lever allowing the carriage to pass in either direction without hindrance.

The place of the carriage-axle is indicated by the pin O, seen in figs. 1 and 2. If preferred, the said lever M can be operated by a projection from any convenient part of the carriage instead of by its axle. The lever G has a horizontal arm or shoe, J, which is arranged so as to project forward from it at a point near to its fulcrum, as shown in fig. 1. The forward end of the shoe has a bevelled face that inclines downward, so that it may be acted on by a projection, K, arranged on the carriage in such a manner that when the carriage runs in and approaches near to the head, the projection will force the arm J downward, and thereby vibrate the lever G so as to bring its upper part forward away from the shipper. The downward movement of the shoe J is limited by a stop, P, which projects from the frame below the arm or shoe J, as seen in fig. 1.

The standard N is here shown adjusted so as to bring the lever M in the proper relations with the axle of the carriage for the operation of spinning hard-twist yarn. When the jack is spinning hard twist the cam F is brought against the shoulder *g* of the shipper, (so as to bring the belt on the edge of the fast pulley,) while the carriage is in the act of "backing off." To accomplish this result I adjust the standard N so as to bring the angle or vertices of the inclinations on the horizontal portion of lever M beneath the axle O of the carriage when the latter has got to the end of its outward movement. From this position the carriage is drawn inward a little distance, two or three inches, more or less, by the strain produced by the twist on the yarn that has just been spun in running out, the extent of such inward movement depending on the hardness of the twist. The horizontal portion of the lever M will be momentarily depressed by the axle of the carriage as the latter gets to the end of its outward movement, and the cam F will be moved toward the shipper, but will not act upon it, because at this stage the shipper will not have been moved (by the devices that change it from the fast to the loose pulley, already referred to,) far enough to the right to bring the shoulder *g* within reach of said cam F, and consequently the weight of the arm or shoe J is left free to restore the levers G and M to their former positions, where the latter will be in readiness to be again depressed when the axle of the carriage next strikes it. As this inward movement of the carriage causes the yarn to kink, and some of it to wind on the bobbins, it becomes necessary to unwind and straighten the yarn before the carriage runs in. This is accomplished by "backing off," as it is technically termed, or in other words drawing the carriage again outward toward the end of its track, by which movement the axle O is brought back toward the lever M, whose horizontal part it gradually depresses as the axle rides over its ascending inclination to the vertex, whereby, through the rod I, or other means which may be employed for connecting the parts, the cam F is brought against the shoulder or other projecting part *g* of the shipper, so as to move the latter a little distance toward the right, (observing fig. 3,) and bring the belt partially on the edge of fast pulley, or far enough to put the belt in motion, and through it the race-shaft, and thereby cause the yarn to be wound on the bobbins and the carriage to be drawn in toward the head of the jack. The degree of the engagement of the belt with the fast pulley is determined by the extent of the movement of the shipper by cam F, which is regulated by the adjustment of the several parts at pleasure.

The engagement of the belt with the fast pulley is not made complete, so as to make the belt run at full speed, but is only partial, so that the belt will be allowed to slip over the edge of the pulley while the latter revolves, so that the belt acquires only a low speed.

When the carriage has run in so far as to bring arm K up to the shoe J, the latter is depressed by the arm, and the cam F is moved away from the shipper, which is then allowed to yield to those devices of the jack whose office it is to move its belt-fork over the loose pulley. This office is performed in this example by the spring R, seen in fig. 3. While the carriage is running in the cam F is prevented from falling away out of contact with the shipper by the friction between the shoulder *g* and the cam; said friction being sufficient to counteract the weight of the shoe J and hold up said shoe until the latter is depressed by the arm K of the carriage.

In spinning soft twist the axle of the carriage is allowed to pass both inclinations of lever M, so that when it stops it will be beyond or forward of the lever, or over that portion of the lever which is too low to be acted on by said axle. Accordingly it is necessary to adjust the lever to a position a little inward from the position in which it is shown in the drawing. Such adjustment is made according to this example of my invention by changing the position of the standard N; the rod I, when a rigid rod is used, being shortened by means of nuts and screws or pins, or other devices used to fasten it to the lever M.

When the carriage runs out in spinning soft twist, it passes over the lever M and depresses its horizontal arm momentarily; but said arm is raised again, after the axle O has passed its angle or the top of its inclinations, by the weight of the shoe J, as before explained, the shipper-bar being under the control of the gear of the jack as soon as said jack is thrown in gear, and consequently entirely free of the cam F; the belt being during this period on the fast pulley. When the carriage is started back the shipper-bar D is released and allowed to drop against the cam, causing the belt to move from the fast on the loose pulley, and as the shaft O passes over the lever M, in the backward motion of the carriage, it causes the belt to shift from the loose partially on the fast pulley so as to create the required friction; the pressure made on the shipper by the spring R, or other device used to force it toward the left, causing friction enough between the shipper and the cam to hold the latter stationary until the carriage has nearly reached the head, when the arm K strikes the shoe and frees the shipper. The same result can be accomplished by moving the fast pulley itself, or by moving the driving-shaft so as to bring the fast pulley into partial engagement with the belt.

I have shown in figs. 4, 5, and 6, a modification of my invention, wherein the lever G is made to act upon and produce a slight longitudinal movement of the driving-shaft B instead of the shipper; the ordinary action of the shipper not being interfered with in its connection with the clock or other parts of a jack. The said driving-shaft B is so arranged in its bearings as to allow it to have a slight longitudinal movement when it is acted upon by the lever G. A spring, R, is so applied to said shaft as to push it always toward the right, observing fig. 6, and hold it by the force of said spring in proper position for the usual changes of the belt at all times when the spring is not overcome by the said lever.

The lever G, which has the cam F at its upper end, as before explained, is mounted loosely upon the driving-shaft next to the fast pulley, up against which it is held by a collar, S, which is fixed on the shaft. The cam F, when the lever G is vibrated, as hereinbefore explained, comes against any fixed object which is in its path, and, by reason of its angular or cam-shaped side or other surface, causes the shaft B itself to be moved along with lever G a little distance toward the left, according to the degree of angularity of the cam, or the extent of its vibration; or both combined, thereby bringing the edge of the fast pulley C partially under the

edge of the belt. In this modification I have made use of the shipper for a bearing surface for the cam F to act against in order to produce the required lateral movement of the lever G; the shipper at this time being held stationary, with its fork over the loose pulley, by a spring or other device which is able to resist a greater force than the power of the spring R and the inertia of the shaft in its bearings.

The shipper has a slot or notch, T, cut on its lower edge, at a suitable point, to allow the end of the cam F to enter the notch. The side of the cam, as the lever G is vibrated, bearing against the right-hand edge of the slot, and causing the lever and the shaft to be moved toward the left by reaction.

My improvement can be further modified in its details and application to jacks of different styles without departing from the principle of the invention as herein set forth.

What I claim as new, and desire to secure by Letters Patent, is—

1. The lever G, having a cam, F, at a suitable point thereon for acting against the belt-shipper, substantially as described.
2. The adjustable standard N and lever M, in combination and arranged to operate with the carriage of a spinning-jack, substantially as described.
3. The combination of the adjustable standard N, lever M, lever G, and connecting-rod I, or an equivalent connecting device, substantially as described.
4. The levers M and G, applied to the shipper D or the driving-shaft of a jack for the purpose of bringing the fast pulley C into partial engagement with the race-shaft belt, substantially as and for the purpose above set forth.

The above specification signed by me this twenty-eighth day of February, 1867.
